UNITED STATES PATENT OFFICE.

LOUIS VICTOR THOMAS, OF LYON, FRANCE, ASSIGNOR TO LA SOCIETE ANONYME DU MOTEUR L. THOMAS, OF LYON, FRANCE.

TWO-STROKE-CYCLE INTERNAL-COMBUSTION ENGINE.

1,402,683.

Specification of Letters Patent.

Patented Jan. 3, 1922.

Application filed July 8, 1919. Serial No. 309,326.

To all whom it may concern:

Be it known that I, LOUIS VICTOR THOMAS, a citizen of the French Republic, of Lyon, France, have invented certain new and useful Improvements in Two-Stroke-Cycle Internal-Combustion Engines, of which the following is a specification.

The present invention consists in a two-stroke cycle internal combustion engine 10 wherein the distribution is effected by means of a reciprocating slide valve, which is actuated by the motor shaft and may be associated with gear for actuating a magneto.

The invention is illustrated in the accompanying drawing, which shows by way of example, one form of construction of the motor.

Fig. 1 is an elevation partly in section on line 1—1 of Fig. 4.

20 Fig. 2 is a section on line 2—2 of Fig. 1. Fig. 3 is a section on line 3—3 of Fig. 2. Fig. 4 is a section on line 4—4 of Fig. 1.

a *a'* designate the cylinders, each communicating by means of ports *b* and *c* with a box *d* at one side of the cylinders. The box *d* contains a gas chamber *m* and a cylindrical valve chamber 8 for the slide valve, the chamber 8 having near its ends ports 7 opening into the chamber *m*. The valve is composed of a tubular body *e* closed at its ends by covers *f* *f'* which hold in place the packing rings *g* *g'*. Inside the valve, at its lower central part, there is a boss *h* into which is fitted the conical head *i* of a driver *j*, fixed by a nut *k*. At its upper part the valve has a large port *l* for suction from the carburettor, and the valve also has near its ends two ports *n*, *n'*, which alternately allow suction of the gases into the pump chambers of the cylinders through ports or channels *o*, *o'*.

For reciprocating the valve, the rod *j* is pivoted at *j'* to the rod *p* of an eccentric *q*, which receives its movement from the motor shaft *r* by means of worm wheels *s* and *t*. The shaft *u*, which carries the worm wheel *t*, also carries a worm wheel *v*, which by means of wheels *x* and *y*, actuates the shaft *z* of the magneto for ignition.

50 The carburettor is mounted on a union 6 above the valve, which facilitates the suction.

Each cylinder *a* or *a'* comprises an upper portion *a''* of a smaller diameter and a lower

portion *a³* of larger diameter. The piston 55 comprises also a portion 2 of diameter corresponding to that of portion *a²* and a portion 5 corresponding in diameter to that of portion *a³*. The piston portions 2 and 5 are integral with one another. The port *c* opens 60 into the larger diameter *a³* of the cylinder which therefore, on the descent of the piston, forms a pump aspirating through port *c* and on the upstroke of the piston forcing the aspirated mixture of air and fuel back 65 through the same port *c*.

During the downward stroke of one of the pistons, say the one on the right in Fig. 2, the part 2 thereof uncovers the port 3, see Fig. 3, through which is effected the exhaust 70 of the gases of combustion. At the same time the port *b* is uncovered, and fresh explosive mixture stored under pressure in the chamber *m* enters the cylinder, toward the top of which it is directed by the deflector 4, 75 and then descends along the opposite wall sweeping before it the residual products of combustion. When the piston has reached the bottom of its stroke the cylinder is, therefore, filled with fresh gas. 80

While the piston is descending, the valve *e* is moved along the chamber 8, until the ports *n*¹ and *o*¹ register. The piston member 5, joined to the part 2, and descending at the same time, sucks gas from the carburettor through the union 6 and the ports *n*¹, *o*¹ and *c*. The valve movement is then reversed, and the ports *n*¹ and *o*¹ are brought out of register. At this moment the piston is at its lower dead point. When it begins its upward stroke, the port 7 is uncovered, placing the chamber 8 in communication with the chamber *m*. The fresh fuel sucked in by the descent of the piston 5 is thus forced during the upward stroke of the piston 95 through the port *c* into the chamber *m*, from which it will pass into the cylinder *a*. A similar cycle of operations takes place for the cylinder on the left, but with a phase difference of 180°. 100

What I claim as my invention and desire to secure by Letters Patent of the United States is:—

In a two stroke cycle internal combustion engine, the combination of two cylinders, 105 each having an explosion chamber and a pump chamber, and each explosion chamber having an inlet port, a gas chamber open to

said inlet ports, a slide valve chamber having near each end two ports, one open to the gas chamber and one open to one of the pump chambers, a hollow slide valve in said valve chamber having an elongated gas inlet port and having also near each end a gas outlet port, and means for reciprocating said valve to place its outlet ports alternately in register with the two ports open to the pump

chambers, and to withdraw the valve from 10 the last mentioned ports.

In witness whereof I have signed this specification in the presence of two witnesses.

LOUIS VICTOR THOMAS.
